UNITED STATES PATENT OFFICE.

BLUMA GROSS, OF JERSEY CITY, NEW JERSEY.

SHIRT.

1,301,252.

Specification of Letters Patent. Patented Apr. 22, 1919.

Application filed October 1, 1918. Serial No. 256,425.

To all whom it may concern:

Be it known that I, BLUMA GROSS, a citizen of the United States of America, residing at Jersey City, in the county of Hudson and State of New Jersey, have invented certain new and useful Improvements in Shirts, of which the following is a specification, reference being had to the accompanying drawings.

10 This invention relates to improvements in shirts and particularly to improvements in outer shirts; and an object of this invention is to provide a shirt by the reversal in position of parts of which pieces of the shirt little exposed to wear may be readily and easily substituted for parts which are normally exposed to the hardest wear, whereby economy of material and labor so necessary in these war-times may be attained.

20 In the drawings illustrating the principle of this invention and the best mode now known to me of applying that principle, Figure 1 is a front view of the shirt, the sleeves of which are shown somewhat disproportionately long in order to attain clearness of illustration; Fig. 2 is an elevation of one of the reversible sections detached; and Fig. 3 is a fragmentary view of the bottom part of a shirt embodying a modified form 30 of this invention.

The feature of this invention resides in the manner in which the sections *a*, *b*, of the front of the shirt *A* are, at their bottom parts, prepared for reversal or made ready 35 for use as the upper parts of the breast of the shirt, which latter parts are the ones that ordinarily become most quickly soiled and, in the course of time, become most quickly worn from repeated laundering and rubbing. Referring more particularly to Fig. 2, the section *a* is ordinarily formed, at its top, with a curved edge *c* along which the collar-band *d* is sewed, a substantially straight edge *e* to which the back *f* is stitched along 40 the shoulder seam *g* (Fig. 1) and a second curved edge *h* along which the upper edge of the sleeve *i* is attached. Quite similarly, the upper part of the section *b* has been cut so as to form correspondingly a collar edge 45 *c'*, a shoulder edge *e'* and a sleeve edge *h'*. The bottom of the section *a* (Fig. 2) is prepared for reversal by forming the edges *j*, *k*, and *m* in the lower end of the sections *a*; and, for a similar purpose, the lower end 50 of the section *b* is formed with the corresponding edges *j'*, *k'*, *m'*.

When the upper part of the front of the shirt *A* has become worn, the sections *a*, *b*, are removed by ripping the collar seams *d'*, the shoulder seams *g*, the sleeve seams *i'* and 60 the side seams *a'*, *b'*. The sections *a*, *b*, are now turned end for end and the sections are transposed, that is, the section *a* is put in the place of the section *b* and the latter in fitted in place of the section *a*. The collar-band *d* is attached to the sections *a*, *b*, along the edges *j*, *j'*, the back *f* is stitched to these sections along the edges *k*, *k'*, the sleeves *i* are fastened in place along the edges *m*, *m'*, and the side seams *a'*, *b'*, are 70 sewed up again. Although the right-hand section *b* ordinarily carries, at its free (or central) edge *b''*, the buttons *n*, it may also be formed with a series of button-holes *n''* arranged intermediate the buttons *n*, as is 75 indicated in Fig. 1; and, similarly, on the free edge *a''* of the section *a*, which ordinarily is formed with a vertical series of button-holes *n'* in which engage the buttons *n*, there might be sewed buttons intermediate the button holes *n'* and arranged to engage in the buttonholes *n''*, after the reversal of the front sections *a*, *b*, has been made; but it seems to me preferable to indicate by suitably small markings *n^x* where 80 the buttons are to be sewn, after the front sections *a*, *b*, have been removed preparatory to reversal, thereby avoiding any objection that may be urged against the showing of too many or superfluous buttons. After the 90 front sections *a*, *b*, have been removed preparatory to reversal, the buttons *n* may be cut from off the section *b* and sewed upon the other section at the points indicated by the small markings *n^x*.

As is clearly indicated in the lower part of Fig. 1, the edges *j*, *j'*, *k*, *k'*, *m*, *m'*, may be finished or faced with a hem or binding *o*, which would ordinarily be removed before the collar-band *d*, the back *f* and the sleeves 100 *i* are stitched to these edges, after the reversal of the sections *a*, *b*, as hereinbefore explained.

In order to provide against the objection that the bottom of the front of the shirt *A* is oddly shaped, the latter may, as shown in Fig. 3, be provided with markings *j''*, *k''*, *m''*, along which the bottom ends of the front sections *a^x*, *b^x*, would be cut preparatory to their reversal; by thus proceeding, 110 the shirt *A'* retains its usual shape prior to the reversal of the front sections *a^x*, *b^x*.

I claim:
A shirt including shirt sections characterized in that the latter are prepared for end-for-end reversal and attachment of their bottom ends to the other parts of the shirt at the top thereof.

In witness whereof, I hereunto set my hand

at Jersey City, New Jersey, this 27th day of September, A. D. 1918, in the presence of the two undersigned witnesses.

BLUMA GROSS.

Witnesses:

SADIE GROSS,

ISAAC GROSS.
